UNITED STATES PATENT OFFICE

AARON A. GOLDSTEIN, OF BUFFALO, NEW YORK

STERILIZING CASE

Application filed January 31, 1929. Serial No. 336,543.

The principal objects of the invention are, to provide a means for effectively sterilizing clinical instruments which may be readily carried in the pocket and will retain the sterilizing fluid from escaping.

A further and important object is to provide a case which will accurately measure a small quantity of the sterilizing fluid and permit it to be discharged for use with a hypodermic syringe.

A still further object is to provide a case that will effectively protect the instrument while the sterilizing liquid reservoir is being refilled.

The principal feature of the invention consists in the novel construction of the case, whereby the slidably tubular instrument holder is extended into a fluid well to sterilize the instrument and upon removal of the instrument effects the sealing of the well.

In the drawings, Figure 1 is an elevational view of my improved case.

Figure 2 is a longitudinal sectional view showing a hypodermic syringe therein.

Figure 3 is a longitudinal sectional view of the case showing the cover removed therefrom and the fluid well sealed.

Figure 4 is an enlarged detail perspective view of the inner sliding tube and spring removed from the casing, said inner tube having the valve end removed.

A pocket sterilizing case for the use of physicians and for the use of persons requiring frequent hypodermic applications is very important in that it enables the use of instruments without danger of infection.

In the construction herein shown the case is formed of a barrel portion 1 which is open at both ends and formed with the inner bore slightly reduced to form a shoulder 2 and a counterbore 3 is formed at the outer end of the reduced bore forming a valve seat.

The ends of the barrel 1 are slightly reduced and provided with external threads 4 and 5.

A closed casing 6 is threaded on to the threaded portion 4 and forms a closed well at the reduced end of the barrel.

A cap 7 is provided to thread on to the threaded portion 5 of the barrel to close the

upper end, said cap being provided with a suitable clip 8 to hold it securely in the pocket.

Within the barrel 1 is arranged a tube 9 preferably formed of a non-corrosive metal, said tube being slidable in the reduced portion 10 of the barrel.

The outer end is formed with an outward flange 11 slidably engaging the inner bore of the barrel.

A coil compression spring 12 encircling the tube 9 and enclosed between said tube and the barrel engages the flange 11 at one end and the shoulder 2 at the other end.

The tube 9 is provided with a laterally extending flange 13 at its inner end which is adapted to engage the seat formed by the counterbore 3 and seals the fluid containing casing 6.

The flange is preferably formed by a threaded cap 14 which is threaded in through the inner end of the tube 9.

A plurality of holes 15 are cut through the wall of the tube 9 above the valve flange 11 so that when the tube is depressed into the fluid casing 6, the sterilizing fluid will enter the end of the tube and when the casing moves outwardly to the position shown in Figure 2, the fluid will drain out from the tube, leaving a small quantity in the cap end when the fluid casing 6 has been sealed.

The flanged outer end of the tube 9 is chamfered on its inner periphery and forms a seat against which the bevelled portion 16 of the hypodermic syringe 17 engages.

The needle 18 of the syringe extends close to the bottom of the tube 9 but cannot touch the tube and when the said tube 9 is depressed into the well formed by the casing 6 and the cap 14 is secured on the outer end of the barrel 1, the sterilizing fluid completely surrounds the needle.

In the use of this device the well casing 6 may be removed at any time for replenishing the sterilizing fluid therein and the syringe needle is protected by the tube 9. The tapered end of the syringe engaging the bevelled seat at the outer end of the tube prevents the escape of the sterilizing liquid from the tube 100.

9 if the case is inverted or laid in a horizontal position.

When the cap is removed the spring 12 forces the tube 9 outwardly and the syringe with it until the valve end closes into the counterbore sealing the casing 6.

The liquid drains out with the exception of a small quantity retained in the cap end and this is used in cleansing the skin before the inserting of the needle in the skin.

10 When the syringe has been removed from the case the closure of the casing 6 by the valve prevents the escape and loss of the sterilizing fluid.

15 A device such as described is extremely useful. Its construction is rugged and will withstand considerable abuse without damage.

20 It has been shown particularly applied to the use of a hypodermic syringe but it may be used with equal facility and benefit with other small clinical instruments.

What I claim as my invention is:—

1. A sterilizing case, comprising a cylindrical barrel threaded at the ends, a well casing threaded on to one end of said barrel, a tube slidably arranged within said barrel having a flanged end adapted to engage the end of the barrel in double sealing contact 30 to close the passage between the barrel and well casing, said flanged end acting as a stop to limit the outward movement of the tube, said tube being open at the other end and having perforations adjacent to its flanged 35 end, a cap threaded on the other end of the barrel and spring means for operating said tube to seal said well casing.

2. A sterilizing case, comprising a cylinder open at the ends and having the bore thereof 40 reduced at one end and an annular valve seat surrounding the outer end of said reduced bore, a tube slidably arranged in the reduced bore and having an annular flanged head forming a valve to engage said cylinder seat 45 and a flanged inner end engaging the larger bore, a spiral compression spring encircling said tube within the larger bore and engaging the flange of said tube to hold the valve end thereof against said seat, said valve and seat 50 forming a stop to limit the movement of said tube, perforations in the slidable tube adjacent to the valve end, a casing enclosing the valve end of the cylinder and forming a well to contain a sterilizing fluid, and a cap closing 55 the other end.

3. A sterilizing casing, comprising a cylinder having a well at one end adapted to contain a sterilizing fluid and a reduced bore intermediate of its length, a tube slidable in 60 said reduced bore having a valve at its inner end and holes through the side wall adjacent to said valve to permit the fluid to enter the tube on depression, the other end of said tube being flanged outwardly and formed with a 65 tapered seat, a spring encircling said valve

and holding the valve end closed, an instrument adapted on insertion into said cylinder to engage said tapered seat at the outer end of said tube and depress the latter and having a tapered portion to fit the seat of said tube to form therewith a liquid seal to prevent the outward escape of said fluid from said tube into the barrel interior when said tube is depressed, and a cap threaded on the end of said cylinder to engage the instrument and depress the slidable tube against the spring pressure to extend the perforated end into the well.

4. In a sterilizing holder for instruments, the combination of a casing adapted to house the instrument to be sterilized and having a separate sterilizing fluid compartment at the lower end, and a tube resiliently supported in said casing having a seat adapted to form a seal against said instrument to prevent the passage of fluid from the tube into the casing and having its lower end perforated and adapted to extend into the fluid in said compartment.

5. In a sterilizing holder for instruments, 90 the combination of a casing adapted to house the instrument to be sterilized and having a separate sterilizing fluid compartment at the lower end, a tube resiliently supported in said casing having a seat adapted to form a seal against said instrument to prevent the passage of fluid from the tube into the casing and having its lower end perforated and adapted to extend into the fluid in said compartment, and valve means carried by said 100 tube forming a seal between said fluid compartment and the interior of said tube when the instrument is removed from its sealing engagement with said tube.

6. In a sterilizing holder for instruments, 105 the combination of a casing adapted to house the instrument to be sterilized and having a separate sterilizing fluid compartment at the lower end, a tube resiliently supported in said casing and having a pair of valve faces, 110 one of said valve faces being adapted to be engaged by the instrument in sealing contact when the latter is placed in the casing to prevent the escape of fluid into the casing, the other valve face of said tube being adapted when the instrument is removed to form a seal at the inner end of said tube to prevent the escape of fluid from said fluid compartment.

7. A sterilizing case comprising a cylindrical barrel adapted to house the instrument to be sterilized, a counterbore at one end of said cylinder forming a pair of angularly related valve seats, a fluid container removably secured on the counter-bored end of said cylinder enclosing said valve seats, a tube slidably mounted in said cylinder having one end extending into said container and formed with an annular shoulder presenting a pair of angularly related valve faces adapted to form 125

a double seal against the aforesaid valve seats, spring means for maintaining said seal when the instrument is removed from the barrel, and closure means for the outer end of the barrel.

- 5 8. A sterilizing case comprising a cylindrical barrel adapted to house the instrument to be sterilized, a counterbore at one end of said cylinder forming a pair of angularly related valve seats, a fluid container removably secured on the counter-bored end of said cylinder enclosing said valve seats, a tube slidably mounted in said cylinder having one end extending into said container, a measuring cup 10 secured in the lower end of said tube, said measuring cup being formed with an annular flange presenting angularly related sealing surfaces adapted to form a double seal with said angularly related valve seats and 15 form a stop to limit the outward movement of said tube, spring means for moving said tube outwardly, and closure means for the outer end of said barrel.
